DESIGN FOR A CONVERTIBLE EVENING DRESS

Max Rosenbluth, New York, N. Y.

Application October 12, 1938, Serial No. 80,400

Term of patent 3½ years

To all whom it may concern:

Be it known that I, Max Rosenbluth, a citizen of the United States and a resident of the city of New York, in the county of New York and State of New York, have invented a new, original, and ornamental Design for a Convertible Evening Dress, of which the following is a specification, reference being had to the accompanying drawing, constituting a part thereof.

Fig. 1 is a front view of a convertible evening dress showing my new design.

Fig. 2 is a rear view of the dress shown in Fig. 1.
Fig. 3 is a front view of the dress as shown in Fig. 1 with the sleeves removed.

Fig. 4 is a rear view of the dress as shown in Fig. 3.

I claim:

The ornamental design for a convertible evening dress, substantially as shown.

MAX ROSENBLUTH.
